JOSEPH C. COULOMBE, OF DRACUT, MASSACHUSETTS.

SUCTION-OPERATED LIQUID-FEED DEVICE.

1,408,801.

Specification of Letters Patent.

Patented Mar. 7, 1922.

Application filed April 19, 1918. Serial No. 229,537.

To all whom it may concern:

Be it known that I, JOSEPH C. COULOMBE, a citizen of the United States, and a resident of Dracut, in the county of Middlesex 5 and State of Massachusetts, have invented certain new and useful Improvements in Suction-Operated Liquid-Feed Devices, of which the following is a specification, the accompanying drawings forming a part 10 thereof.

The invention relates to devices of the type commonly known in the art as "vacuum feed" devices; that is, a device operated by an induced suction for raising a liquid 15 from a low level to a high level and distributing it to the engine or like device.

The object of the invention is to provide an improved device, of the type indicated, for supplying liquid fuel and for controlling 20 the movement of said supply.

The particular objects are hereinafter set forth in the accompanying description and claims.

Referring to the drawings:

25 Fig. 1 is a diagrammatic view illustrating a portion of an internal combustion engine and connections therefrom to the "vacuum feed" device.

30 Fig. 2 is a vertical section through the casing of the vacuum feed tank.

Fig. 3 is a top plan view of the device of Fig. 2 with parts broken in section.

Fig. 4 is a vertical section through the distributor.

35 Fig. 5 is a vertical section through the trap.

Fig. 6 is a sectional view through the circulating pump showing a constant level chamber.

40 Referring to the drawings, E, indicates an internal combustion engine; V, the suction operated fuel feed or tank; C, the carbureter of the engine which delivers the carbureted fuel through manifold M, to the in- 45 take side of the engine.

The oil-circulating pump is denoted at O, and has an inlet connecting pipe o', which extends to the "sump" through the motor casing, and an outlet or distributing 50 pipe line o'', which carries the lubricant to the various bearings of the engine in any well known manner.

R, denotes a radiator used in the water-cooling system for the engine, the water be-

ing circulated through the jacket of the 55 engine in well known manner by a circulating pump P.

S, indicates the fuel supply tank which is ordinarily located at a level lower than the feed device V, and carbureter C.

60 The supply tank S, is connected with the vacuum feed device V, through a fuel line s.

The carbureter C, is connected to the vacuum feed V, through a pipe c.

s', denotes a suction connection from the 65 vacuum feed V, to a distributor D.

s², s³, denote suction connections from the distributor D, extending respectively to the manifold M, and to a low pressure point in the oil-circulating system, preferably the 70 inlet side of the oil-circulating pump O.

Whether the suction, for operating the vacuum feed V, is induced by the manifold 75 of the engine, or a circulating pump, or other means connected with the engine is immaterial so far as the detail of operation of the vacuum feed device is concerned. Certain advantages in the maintenance of a proper degree of suction under all conditions of running of the engine may be secured by those connections hereinabove indicated.

As is well-known, there is a sub-atmospheric condition existing in the manifold of an engine, which varies in intensity as the 85 throttle valve is closed. It is also true that a sub-atmospheric condition may be induced in the oil-circulating system, the intensity of which varies with the speed of the motor and circulating pump. It follows that, with the engine operating on open throttle and at high speed, there is comparatively little suction effect induced at the manifold, but there is an increased suction effect produced by the circulating system.

90 Advantage may be taken of these conditions by utilizing the connections indicated in conjunction with the distributor D.

95 This so-called distributor has a main chamber d, which connects with the suction connection s'. Suitable check valves d', d'', control openings from this chamber d, to the respective suction connections s², s³. With this arrangement, whichever suction predominates in intensity will react through the chamber d, and suction connection s', to cause the necessary sub-atmospheric condition in the vacuum feed V; and, of course,

if the suction is substantially equal in both of the suction lines s^2 , s^3 , both of the valves d' , d^2 , will open so that the combined suction is effective in the chamber d , and its connection s' .

The degree of suction in the liquid-circulating system may be modified within reasonable limits by restricting the flow to the inlet side of the circulating pump, as indicated, 10 and locating the suction connection s^3 between said point of impedance and the circulating pump. This arrangement permits of arranging for a definite degree of suction at the slowest speed of the circulating 15 pump.

In Fig. 6, a form of circulating pump is illustrated with means for adjustably restricting the inflow to the pump and with means for maintaining the pump in condition 20 for producing suction immediately upon rotation of its parts. The inlet opening t , is controlled by a valve member t' , mounted upon a stem t^2 , so arranged that the restricting valve t' , may be set to cause a 25 greater or less restriction at the inlet opening t .

The pump, as illustrated, is of the gear or lobe type of well known construction, having the rotary members u , u' . Arranged 30 in the casing of these members, there is a chamber or wall u^3 , which will always maintain a level of liquid sufficient to immerse the rotary members u , u' . In order to prevent siphoning back of the liquid from the chamber u^3 , a nipple u^4 , may be formed at the inlet side of the chamber so that the flow by siphon effect will be broken as soon as the level of liquid in the chamber u^3 , falls below the end of the nipple u^4 .

40 Ordinarily, in circulating pumps, there is an interval upon starting the pump when little or no circulation takes place. In fact, the pump must be brought up to a considerable speed before it will create sufficient 45 suction to circulate a liquid. This is largely due to the fact that the liquid forms a packing for the pump; and when the pump is not in operation, the liquid drains back and destroys the packing effect.

50 In the arrangements illustrated, a draining back of the liquid to the pump will insure the filling of the chamber u^3 . It follows that the rotary members of the pump are immersed and packed in the liquid so that, upon initial rotation of the gears or lobes of the pump, suction will be created to draw up liquid through the inlet connection o' , and create a suction in the suction line s^3 .

60 The vacuum feed device V , which is operated by a suction however induced in the suction line s' , consists essentially of an operating or suction chamber 1, enclosed by a casing 2; a liquid seal chamber 3, having 65 a casing 4, (said chamber 3 and casing 4 ar-

ranged within the operating chamber 1); a distributing chamber 5, having a casing 6, within which the casing 2, telescopes; and valve devices and connections, as hereinafter defined.

Upon the top of the casing 2, there is a manifold 7, to which the fuel connection s , and suction connection s' lead. This manifold consists of a block having a connecting nipple 8, and union 9, which secures the end 70 10, of the fuel pipe s , in place. The connecting nipple has a bore of sufficient size to receive the tubular strainer 11, which may be secured to the end of the fuel pipe s . This bore extends into a vertical opening 80 12, closed by a priming cap 13. The latter gives access to the interior of the chamber 1, for the purpose of filling same.

The vertical opening 12, connects with the casing 2, and there is a valve seat 14, and 85 a valve 15, co-operating therewith to shut off the flow of fuel to the chamber 1, at predetermined periods.

The manifold is also provided with a suction connection 16, which opens into the 90 liquid seal chamber 3. Intermediate the suction connection 16, and the suction distributor D, there is a "trap" casing 17, provided with a valve 18, operated by a float 19.

The valve 18, controls a valve opening 20, 95 and cuts off suction of the suction line s' , whenever liquid rises into the chamber of the "trap" and raises the float 19.

It will be noted that the float is arranged in a vertical chamber and that the suction 100 line s' , is connected above the chamber, while the lower end of the chamber is connected through the nipple of the suction connection 16. In this position, the trap will always be self-drained. The float 19, and 105 valve 18, prevent fuel being drawn over into the suction line s' .

The suction connection 16, opens into a vertical chamber 21, of the manifold 7, and communicates with the liquid seal chamber 110 3, through a valve opening 22, preferably formed in the end of a guide tube 23, having a perforation or suction opening 24, within the chamber 3. The guide tube 23, serves as a guide and support for a float 25, and 115 has a valve stem 26, secured at its lower end to the float and moved thereby to control the valve opening 22.

The float 25, is arranged to move within the tubular casing 4, of the liquid seal chamber 3, and is provided at its lower end with a baffle 27, which protects the lower edge of the casing 4.

The float 25, through a pivoted lever 28, and valve stem 29, controls a valve 30, which 125 serves to control a valve opening 31, which is the only source of communication between the operating or suction chamber 1, and the distributing chamber 5.

The valve 30, has a central perforation 130

and a beveled valve-seat 32, against which is normally seated a ball valve 33, which is adjustable with reference to the valve stem 29.

5 This ball valve 33, is opened by the first movement of the float 25, in order to permit said float to operate the large valve 30, an opening of which permits the liquid of the chamber 1, to fall by gravity into the chamber 5, as soon as the relative pressures of the chambers 1 and 5, have sufficiently equalized. The chamber 5, is subject to atmospheric pressure owing to the loose connection between the telescoping walls 2 and 6. In 15 other words, there is no seal between the walls 2 and 6, and therefore the chamber 5, is under normal atmospheric pressure.

The valve 15, has an extended stem 15^a, which rests upon the lever 28, or a cam plate 20 28^a, secured thereto. This valve 15, is held in open position during the closed position of the valve 30, and closes in the direction of flow of liquid to the chamber 1, as the float 25, rises and opens the valve 30.

25 The liquid seal chamber 3, has a connection from its upper end to a point below its lower end, which connection opens into the chamber 1, and is illustrated herein as a tubular member 34. This connection serves to 30 break the liquid seal of the chamber 3, whenever the level of liquid in the chamber 1, falls below the lower end 35, of the connection 34.

The telescoping casings 2 and 6, permit of 35 the use of a strainer between the bottom of the chamber 1, and the outlet of the distributing chamber 5.

As illustrated, there is an annular rib 36, in the interior of the chamber 5, which supports the chamois strainer 37, the latter being held in place by a suitable ring 38. This arrangement serves as a convenient means for thoroughly straining all fuel which passes through the distributing 45 chamber 5, as it may be readily removed and cleansed by slipping the inner casing 2, out of the casing 6. The lower end of the casing 6, is provided with a fitting 39, with a connecting opening 40, for the pipe connection *c*. It is also provided with a drain plug 41, which has a valve 42, closing an opening 43, in the bottom of the casing.

The valve 42, is arranged upon a reduced 55 end of the plug 41, which is provided with a transverse opening 44, communicating with a vertical opening 45. This arrangement permits a partial turning of the plug 41, to open the valve 42, whereupon the chamber 5, may be drained through the plug.

60 The operation of the device is as follows: Suction is induced through the suction connection *s'*, and, with the valve and valve mechanism in the position shown, fuel will be drawn into the chamber 1, until it reaches 65 the lower edge of the liquid seal chamber 3.

It will then continue to rise in the liquid seal chamber 3, without rising in the operating chamber 1, until the float 25, becomes sufficiently buoyant to operate the valve 30. Thereupon, the suction in the chamber 1, 70 will be sufficiently neutralized to permit the liquid of said chamber 1, to flow by gravity into the distributing chamber 5, and this flow will continue until the level in the chamber 1, falls below the end 35, of the 75 connection 34. Air will then be admitted to the liquid seal chamber 3, breaking the partial vacuum existing therein and permitting the contents of the chamber 3, to fall with the float 25. The float in this movement 80 closes the valve 30, and the operation is repeated. When the float 25, rises to its full height, it cuts off the suction by closing the valve opening 22.

It will be observed that with this arrangement there is a distinct timing in the 85 operation of the valve mechanism. The float will not rise to open the valve 30, until after the level in the chamber 1, has reached the lower edge of the liquid seal chamber 3, 90 and risen in the said chamber 3, to a point to make the float 25, buoyant.

The first movement of the float, as it becomes buoyant, opens the valve 33, thus reducing the degree of vacuum in the chamber 95 1. An increase of pressure in this chamber 1, immediately drives the liquid higher in the chamber 3, and the float breaks open the valve 30, with a snap or quick movement and, thereupon, the suction opening 22, is 100 closed by its valve.

The float 25, will remain in its uppermost position, holding the valve 30, open until the partial vacuum in the chamber 3, is broken by opening the lower end of the 105 connecting tube 34, to the pressure conditions of the chamber 1. This will only occur when the liquid has fallen below the end of the tube 34, and, until such time, the float 25, remains buoyant in the liquid of the 110 chamber 3, and held under partial vacuum which is greater than that of the chamber 1.

It will be apparent that as soon as the bottom of the chamber 3, is sealed by the liquid, the rise of level in the chamber 3, will 115 be much more rapid than that in the chamber 1, thus insuring operation of the float 25, and valve 30, and the flow of liquid from the chamber 1, to the chamber 5, before there can be any flooding of the chamber 1.

With this arrangement, definite levels may be maintained during the operation of the device and liability of flooding of the chamber 1, is obviated, as there is a sufficient time period allowed for insuring the operation of 125 the float without unduly raising the level in the chamber 1. Furthermore, there is little liability of the valve 30, closing until the chamber 1, is completely drained. It follows that measured quantities of liquid may 130

be delivered by the chamber 1, to the chamber 5, thereby obviating difficulties heretofore existing in vacuum feed devices.

It will be observed that when the liquid 5 rises in the chamber 1, it seals the lower edge of the liquid seal chamber 3. It is obvious that the connection 34, may be made in any desired manner, so long as the upper portion of the chamber 3, is connected with 10 the lower portion of the chamber 1, thereby maintaining a lower vacuum in the chamber 3, than exists in the chamber 1, until the contents of the chamber 1, has drained into the chamber 5.

15 While the suction connections for producing vacuum have been illustrated in conjunction with the oil circulating system and pump of the engine, it is obvious that any circulating system employed on the engine 20 might be used. There is an advantage, however, in employing the oil circulating system as it gives an immediate indication to the operator when the oil fails. This, of course, is a safeguard against overheating of the 25 engine, as failure of the circulating system would cause a loss in suction with open throttle condition of the engine and no fuel would be fed to the carbureter.

What I claim as my invention and desire 30 to secure by Letters Patent is:

1. In a fuel feeding device, a suction chamber, a float and valve mechanism controlling the level of liquid of said suction chamber, a liquid seal chamber controlling said mechanism and sealed by a rise of liquid in the 35 suction chamber, and a connection between the liquid seal chamber and the suction chamber, said connection being controlled by the rise and fall of level of liquid in the 40 suction chamber.

2. In a fuel feeding device, a suction chamber, a valve and float mechanism controlling the level of liquid of said suction chamber, a liquid seal chamber controlling said mechanism and sealed by a rise of liquid in the 45 suction chamber, and a connection between the liquid seal chamber and the suction chamber, said connection being closed and opened by the rise and fall of level of 50 liquid in the suction chamber and thereby controlling the action of the liquid seal chamber upon the valve and float mechanism.

3. In a fuel feeding device, a suction chamber, a liquid seal chamber, the latter opening at its bottom to the former and adapted to be sealed by a rise of liquid in the suction chamber, a valve and float mechanism controlling the action of the suction chamber and the level of liquid therein, and means 55 for breaking the seal of the liquid seal chamber after the level of liquid of the suction chamber has been lowered below the bottom of the liquid seal chamber.

4. In a fuel feeding device, a suction chamber, a valve and float mechanism controlling

the level of liquid of said suction chamber, a liquid seal chamber opening into the suction chamber and adapted to be sealed by rise of level of liquid in the suction chamber, a suction connection communicating with the 70 liquid seal chamber, and means for neutralizing the suction of the liquid seal chamber after the level of liquid in the suction chamber has dropped below the sealing level of said liquid seal chamber. 75

5. In a fuel feeding device, a suction chamber, a valve and float mechanism controlling the level of liquid of said suction chamber, a liquid seal chamber opening into the suction chamber and adapted to be sealed by rise of level of liquid in the suction chamber, a suction connection communicating with the liquid seal chamber, a valve controlled by the float mechanism for opening and closing said suction connection, and 80 means for neutralizing the suction of the liquid seal chamber after the level of liquid in the suction chamber has dropped below the sealing level of said liquid seal chamber. 85

6. In a fuel feeding device, a suction chamber, a distributing chamber open to atmospheric pressure, a valve-opening between said chambers, a valve controlling said opening and admission of air to the suction chamber and the flow of liquid from said chamber 90 to the distributing chamber, a float controlling said valve, a liquid seal chamber surrounding said float and opening at its bottom to the suction chamber, and a connection from the upper portion of said liquid seal 95 chamber to the lower portion of the suction chamber through which connection the relative pressures of the liquid seal chamber and the suction chamber are equalized.

7. In a liquid fuel feeding device, a suction chamber, a distributing chamber open to atmospheric pressure, a valve-opening between said chambers, a valve controlling said opening, a valve seated in said first-named valve and adapted to reduce the suction of the suction chamber, a float controlling both valves, a liquid seal chamber controlling said float, said chamber opening at its bottom to the suction chamber and adapted to be sealed by a rise of level of liquid in said suction chamber, a suction connection communicating with the liquid seal chamber, and means for equalizing the relative pressures of the liquid seal and suction chambers after the level of liquid of 100 the suction chamber has fallen below the float of the liquid seal chamber. 110

8. In a fuel feeding device, an exterior casing member, an interior casing member, said members telescoping one within the other, a fuel supply tank and means for producing suction, a connection communicating with the fuel tank and interior casing, a connection communicating with the interior casing and a source of suction, a 115 120 125 130

delivery connection extending from the exterior casing, an interior support in the exterior casing, and a strainer removably mounted on said support.

- 5 9. In a fuel feeding device, an exterior casing member, an interior casing member, said members telescoping one within the other, a fuel supply tank and means for producing suction, a connection communicating with the fuel tank and interior casing, a connection communicating with the interior casing and a source of suction, a delivery connection extending from the exterior casing, a flange extending about the 70 interior of the exterior casing, a ring fitting said flange, and a strainer supported between said ring and flange.

10. The combination with an internal combustion engine, having a pump driven by the engine for circulating liquid, and pipe connections for said pump through which liquid is circulated; of a fuel feeding device, employing suction for moving fuel for distribution to the engine, a suction connection from said fuel feeding device to the intake side of the circulating pump, and means for restricting the flow of liquid to the inlet side of said pump.

11. The combination with an internal combustion engine, having a pump driven by the engine for circulating liquid, and pipe connections for said pump through which liquid is circulated; of a fuel feeding device, employing suction for moving fuel for distribution to the engine, a suction connection from said fuel feeding device to the intake side of the circulating pump, and adjustable means for restricting the flow of liquid to said pump.

40 12. The combination with an internal combustion engine, having a pump driven by the engine for circulating liquid, and pipe connections for said pump through which liquid is circulated; of a fuel feeding device, employing suction for moving fuel for distribution to the engine, a suction connection from said fuel feeding device to the intake side of the circulating pump, and a restriction interposed in said system between the intake connection of the pump and the suction connection of the fuel feeding device.

13. In combination with an internal combustion engine, a pump driven by the engine for circulating liquid, pipe connections for said pump through which liquid is circulated, a well providing a constant level of liquid for the pump, a fuel feeding device for the engine employing suction for moving fuel for distribution thereto, and a suction connection from said fuel feeding device to the intake side of the circulating pump.

14. In combination with an internal combustion engine, a pump driven by the en-

gine for circulating liquid, pipe connections for said pump through which liquid is circulated, a well providing a constant level of liquid for the pump, a fuel feeding device for the engine employing suction for moving fuel for distribution thereto, a suction connection from said fuel feeding device to the intake side of the circulating pump, and means for restricting the flow of liquid to the well.

15. In combination with an internal combustion engine, a pump driven by the engine for circulating liquid, pipe connections for said pump through which liquid is circulated, a well providing a constant level of liquid for the pump, means for preventing siphoning of the liquid from said well, a fuel feeding device for the engine employing suction for moving fuel for distribution thereto, and a suction connection from said fuel feeding device to the intake side of the 80 circulating pump.

16. In a fuel feeding device, having a suction chamber, a suction connection for said suction chamber, and a trap interposed in 90 said connection, said trap having a float controlled valve for closing the suction connection.

17. The combination with an internal combustion engine, having a carburetor, a lubricating pump, connections from the carburetor to the intake side of the engine, and connections for the pump through which lubricating oil is circulated; of means for restricting the flow of lubricant to said pump, 100 means for feeding fuel to the carburetor comprising a suction feed device, having a suction chamber, a suction connection from said chamber to the intake side of the engine, and a cooperatively related suction connection communicating with the suction chamber and with the oil pump, said connection being made between the said restriction and the circulating mechanism of the pump, a fuel connection for the suction chamber, a 110 connection from said chamber to the carburetor.

18. The combination with an internal combustion engine, having a carburetor, a lubricating pump, connections from the carburetor to the intake side of the engine, and connections for the pump through which lubricating oil is circulated; of means for feeding fuel to the carburetor, comprising a suction feeding device having a suction chamber, a suction connection for said chamber, a trap having a float controlled valve arranged in said suction connection, a distributor communicating with the suction connection, a valve controlled connection 120 extending from said distributor to the intake side of the engine, a valve controlled connection extending from said distributor to the intake side of the lubricating pump, a fuel connection for the suction chamber, 130

a connection from said chamber to the carbureter.

19. In a device of the character described, having a suction chamber, a manifold mounted upon the exterior of the chamber, horizontally disposed nipples extending from said manifold, a chamber formed in one of said nipples, a strainer tube extending into said chamber, means for connecting a fuel pipe to said nipple, means for connecting a suction pipe to the second of said nipples, and connections from said nipples through the manifold to the suction chamber, 10 means for connecting a fuel pipe to said nipple, means for connecting a suction pipe to the second of said nipples, and connections from said nipples through the manifold to the suction chamber.

20. In a device of the character described, 15 having a suction chamber, a manifold mounted upon the exterior of the chamber,

horizontally disposed nipples extending from said manifold, a chamber formed in one of said nipples, a strainer tube extending into said chamber, means for connecting a fuel pipe to said nipple, means for connecting a suction pipe to the second of said nipples, connections from said nipples through the manifold to the suction chamber, and a priming plug closing an opening 20 in said manifold and a chamber closed by said priming plug though communicating with the chamber containing the strainer.
